UNITED STATES PATENT OFFICE.

GUY P. THURBER, OF PITTSBURGH, PENNSYLVANIA, ASSIGNOR, BY MESNE ASSIGNMENTS, TO AUTOMATIC TRAIN CONTROL & SIGNAL COMPANY, OF PITTSBURGH, PENNSYLVANIA, A CORPORATION OF DELAWARE.

SYSTEM OF TRAIN CONTROL.

1,162,890.

Specification of Letters Patent.

Patented Dec. 7, 1915.

Application filed November 5, 1908, Serial No. 461,141. Renewed April 29, 1915. Serial No. 24,795.

To all whom it may concern:

Be it known that I, GUY P. THURBER, citizen of the United States, and resident of Pittsburgh, in the county of Allegheny and State of Pennsylvania, have invented certain new and useful Improvements in Systems of Train Control, of which the following is a specification.

The present invention relates to a system of train control.

The primary object of the invention is to produce a system which will not only indicate abnormal track conditions, but which will also give warning of its own imperfection or breakdown, and this without the use of third-rail or similar devices, the traffic track itself constituting a part of the system.

Other objects will appear as the specification proceeds.

The main feature of the invention centers around a main circuit normally closed and charged, which extends partly through conductors carried by the train and is normally closed through the traffic tracks. The traffic tracks are divided into sections or blocks by insulation, and a normally closed blind shunt or jumper circuit connects adjacent sections of the track. The main circuit is completed through this blind shunt under normal conditions when passing from one section to another. If the blind shunt is broken, the main circuit is broken when passing over the insulation. Under the control of the main circuit are suitable train controlling means, such as signaling devices or throttle and air-brake controlling means, or both. These train controlling means are normally held inoperative, that is to say: so long as the main circuit remains closed and charged. When this circuit is broken these train controlling means become operative and act, according to their capacity, to give signals or to stop the train. The energizing battery for the main circuit is, in the form disclosed, carried by the moving train. Preferably the train controlling means are not directly under the control of the main circuit, but are controlled by means of one or more subsidiary cab circuits normally held closed by the main circuit. The integrity of the main circuit thus depends upon whether or not the blind shunt is closed. This aside from such conditions as a broken rail in the block in which the train is running or imperfections in the connections

carried by the moving train. Accordingly, this blind shunt is under the control of track and line relays of the succeeding blocks, which if any of these relays are deenergized the blind shunt is broken. The arrangement of track and line relays and circuits for accomplishing this may of course vary widely, but in the preferred form these parts take the following form: The track is divided into sections, each section comprising a main and a local block. Both or only one of the rails may be insulated between the main and local blocks of the same section, but both rails must be insulated between the local block of one section and the main block of the adjoining section. Interposed between the local block of one section and the main block of the same section is a blind shunt connection having a relay. Each main and each local block is provided with a circuit and relay, and the line circuits extending between the block sections are also provided with relays. The jumper circuit at a certain section is controlled by the main block relay and line relay. The main block circuit is controlled by the local block relay of the succeeding section. The line wires, of which there are four in the form disclosed, are controlled, one set by the shunt or line controlling relays, of two succeeding sections, while the other set is controlled alternately by the main block relay and the shunt relay at the two succeeding sections. Thus the circuits and relays are interconnected in such a way that a break or a shunt circuiting of any of the circuits, including the traffic tracks, will act to break the blind shunt of two or more sections. When a train therefore arrives at any of these sections the main circuit of the train is broken and the safety devices made operative.

As it is essential to the proper working order of the system that the blocks be electrically insulated from each other, I provide means for detecting any breakdown in the insulation between joints by arranging the batteries of adjacent sections in opposition so that if the insulation should break down, the batteries will neutralize each other.

Certain relays or electro-magnets are used in the system, which when deenergized, due to the rupture of any of the connections or the deflection of the magnetizing current in another direction, serve to break certain cir-

cuits to cause the actuation of the normally inactive train controlling means. When as under certain conditions, the current is deflected to another path of lower resistance for the purpose of deenergizing the relay or relays, enough current might still flow through the relay to enable it to sustain its armature and to thus defeat the very purpose of the relay which is, to drop its armature and break another circuit when it is itself deenergized. To overcome this, I provide a bypass for the current which operates automatically to shunt the current around the relay when the relay is to be thus deenergized.

In the accompanying drawings, is illustrated the preferred embodiment of the invention, but various changes may be made without departing from the scope of the invention.

In the said drawings: Figure 1, is a diagrammatical view of my complete system, representing a train and a portion of the traffic track with their respective equipments, the parts of the system being in their normal state, as when the proper running conditions exist. Fig. 2, is a similar view representing the operation of the system as when two trains are in close proximity on the same track. Fig. 3, is a detail view illustrating a slight modification in the connection of the battery for energizing the main block relay. Fig. 4, is an enlarged view illustrating the wiring of two of the stations.

Like reference characters designate the same parts throughout the several views.

The cab or train circuit, which may be called the controlling circuit, is carried by some part of the train, and is preferably, together with the various train controlling means, located conveniently in the engineer's cab. The circuit is made up of two main conductors 1, a source of electrical supply, which is here shown as a battery 2, and a circuit breaker of some sort, which is preferably in the shape of a relay 3, having an armature 4. In order to insure a positive break in the circuit when for any reason the main relay is deenergized, even if only so temporarily, I prefer to put the armature of the relay in circuit, so that the instant the armature drops, the circuit is broken and cannot be completed, in so far as the actual cab portion of the circuit is concerned, until the armature is restored. For this reason the relay has a short back connection 5, ending in a contact terminal 6, to be engaged by the armature, when the relay is energized to hold its armature in contact with the terminal 6. The relay thus cannot restore its own circuit. The armature is pivoted at the point 7. Train controlling means are either included in this cab or controlling circuit or are included in a subsidiary circuit under the

control of the main cab circuit, so that the said controlling means are actually under the control of the main cab circuit, being either directly or indirectly controlled thereby. This train controlling means will be later described in detail.

To render the controlling circuit responsive to track conditions, the said circuit is led to the track and is completed by the traffic track itself, so that any break in the traffic track acts as a break in the controlling circuit. The controlling circuit is led to the track at two different points, spaced and insulated from each other, so that the traffic track will serve as a conductor for the passage of the current from one point to the other. The circuit is preferably connected to the track at two points, as illustrated in Fig. 1, by insulating two trucks 8, and connecting the ends of the controlling circuit to these insulated trucks.

The track is preferably divided into blocks or sections of any suitable length and this may be done as illustrated in the several views, by placing suitable insulation between the joints at the end of each track section.

The principle of the operation of the invention is illustrated in comprehensive form in Figs. 1, 2 and 4, to which attention is directed. When the train is in any one block, the cab circuit is completed through the traffic rails, provided of course that such rails are electrically continuous. Therefore if no other means were provided, there would be a break in the cab circuit as the trucks passed each insulated joint. To overcome this otherwise inevitable break, a normally closed but blind shunt is coupled across the insulated joints. This shunt or bridge between the joints is indicated at 13, and the use of this shunt will be understood from Fig. 4, wherein it will be seen that the shunt under normal closed conditions, bridges the gap across the insulated joints 110 when the train is passing from one block into the next. A battery 14, may be placed in the shunt connection to assist the passage of the current to the return side of the cab circuit and for a certain other use which will appear hereinafter. It will be evident that a rupture in the shunt circuit, will cause a break in the cab circuit and the safety devices normally held inoperative by the normally closed circuit, by reason of such break in the circuit, will become operative. The traffic rails or the shunt, therefore in reality, form a continuation of the cab circuit, and a break in any part of this system will serve to render the safety devices active. I therefore use this shunt as a bridge for the cab or controlling circuit under normal conditions and as a means for disrupting the cab circuit to cause actuation of the safety devices under abnormal or danger conditions.

For this purpose, certain devices are used which are affected by track conditions and which control the shunt. These devices for controlling the shunt are preferably in the 5 shape of certain circuits which are normally closed when proper running conditions exist, but which automatically open when a change from normal running conditions occurs, these circuits in turn containing relays 10 having armatures which when the relays are energized serve to hold the shunt circuit closed, and which, when the relays are de-energized, create an artificial break in the shunt circuit. These circuits, which might 15 be termed "track circuits" are dependent for their action upon the condition of different portions of the track, so that as the conditions of these different portions of track are altered, the track circuits are affected accordingly, and the shunt circuit likewise.

In order to render the system more effective, each section of track preferably consists of a long main block 15, and a short local block 16, the two being insulated one 25 from the other. The joints between the local block and the main block of the same section are preferably staggered as shown at 17. In each local block there is a local circuit 18, including a battery 19, and a 30 local block relay 20. This local block relay controls a double armature or a pair of armatures 21 and 22. In each main block, a main block relay 23, is connected by wires 24, between the opposite rails of the track.

35 Energizing current for the main block relay is derived from a battery 25, which is likewise connected across the rails by conductors 26. This circuit just described and which may be designated as the main block circuit, 40 is under the control of the local block relay, the armature 22, of the local block relay serving, when the local block relay is energized, to engage the contact point 27, and thus close the main circuit. A contact 28, 45 is interposed in the shunt circuit and when the main block relay is energized, the armature 29 of said relay, engages said contact thus serving to close the shunt circuit at that point. There is another contact 30, 50 interposed in the shunt circuit and a corresponding armature 31, to engage this contact, the armature 31, being in turn controlled by the relay 32, which is at the end of the charged line circuit 33. This line circuit 55 is controlled by the local block relay of the second succeeding section, there being a contact 34, in said circuit adapted to be engaged by the armature 21, of the said local block relay. This line circuit is likewise 60 under the control of a relay 35, located at the same section as the local block relay just referred to. This relay is normally energized by the battery 14, the current from said battery passing along a portion of the 65 shunt connection, to the armature 29, and

thence by the contact 36, and conductor 37, through the relay and by conductors 38-26, back to the rail and through the rail to the other pole of the battery. The conductor 26, may serve here as a common return for 70 both this circuit, and the main block circuit. The relay 35, is thus influenced by the shunt connection. The line circuit 33, is also under the control of the relay 35, as the armature 36', of this relay under normal 75 conditions engages the contact 37', in the line wire and serves to complete the line circuit. The line circuit 33, is likewise under the control of the local block relay and the shunt-controlled relay 35, of the next 80 adjoining section in the same way as just described. This line circuit just described is preferably used to render caution signals, and the line circuit 39, is preferably used for the rendering of danger signals.

85 The line circuit 39, terminates in a relay 40, whose use corresponds to the use of the line circuit relay 32, of the next adjoining section, that is, to complete the shunt circuit by holding the armature 31, in engagement with the contact 30. This second line circuit is energized by a battery 41, and is under the control of the shunt-controlled relay 35, of the next adjoining section by means of an armature 42, adapted to be attracted by said relay and to engage the contact 43, in the second line circuit. The second line circuit is also under the control of the main block relay of the second succeeding section and for this purpose a contact 44, is interposed in the circuit which is adapted to be engaged by the armature 45, of the main block relay 23. This may also be a double armature.

100 In order to understand the operation of 105 the system, suppose a train to occupy the main block at the left in Fig. 2. This train is diagrammatically represented by the pair of wheels and axles 46. When in this position the current from the main block battery 25, will be short circuited across the rails by the wheels and axles of the train, 110 thus causing the main block relay 23, to be de-energized. The said main block relay when so de-energized drops its armature 29, 115 and the shunt connection is broken at the point 28. By this same action the shunt-controlled relay circuit is broken at the point 36, and the shunt-controlled relay 35, is de-energized. The de-energization of the shunt-controlled relay causes the double armature 36'-42 of the relay to drop, thereby breaking the first line circuit 33 (caution), at point 37', and the second line circuit 39, 120 (danger) at the point 43. This break in the first line circuit causes the relay 32, at the second preceding section at the end of this line circuit, to be de-energized, dropping its armature 31, and breaking the shunt circuit at the point 30, and causes the relay 125 130

40 at the first preceding section to be de-
energized breaking the shunt circuit of that
section. Then should a second train come
along and reach the second preceding sec-
tion, where the shunt connection is broken,
the cab circuit on the second train cannot
be completed through the shunt connection,
as it would be, if the track conditions were
clear and normal. This break in the shunt
10 portion of the cab circuit causes a caution
signal to be displayed in the cab in the fol-
lowing manner: The armature of the cab
relay is preferably of compound structure
and made in three parts 46, 47 and 48 re-
spectively, so as to establish three different
15 connections, or relatively the same result
might be attained by having a single arma-
ture provided with the proper connections.
For the purpose of giving the signals to the
20 engineer, I prefer to use an electro-mag-
netic indicator 49, which partakes of the na-
ture of a semaphore. This indicator when
the cab circuit is complete is energized by
25 current preferably from the main cab bat-
tery 2, and for this purpose a branch wire
50, is used, which is connected to the main
cab circuit at the point 51. The branch
wire after passing through the indicator
terminates in a contact 52, to be engaged
30 by the armature 47, of the cab relay, said
armature being connected to the other side
of the main cab circuit by a short conductor
53, so that in reality the indicator is con-
nected in parallel across the main cab cir-
35 cuit. Therefore when the main cab circuit
is broken in the manner before described, or
in fact in any manner, the indicator gives a
visual warning to the engineer or other au-
thority in charge. In addition to this, I
40 prefer to use a register for recording the
giving of such signals to the engineer. This
recorder would preferably be in the shape of
a watchman's clock, such as that shown in
Patent No. 822,029, and is indicated at 54.
45 This clock would have two magnets 55 and
56, for recording the giving of signals and
the actuation of the train stopping means
respectively. The clock is preferably nor-
mally on open circuit. A conductor 57,
50 leading from the signal recording side of
the clock, terminates in a contact 58, which
when the armature 46, of the cab relay falls,
is engaged by said armature and a circuit
completed through the clock by way of
55 said armature, the main battery 2, and the
conductor 59. As an additional warning to
the engineer, I prefer to use an audible
alarm such as a whistle 60, this whistle be-
ing controlled by an electro-magnetically
60 controlled air valve 61. This so-called whis-
tle valve has a solenoid part 62, which when
energized, as it normally is, holds the air
valve closed. From the solenoid valve a
pair of conductors 63, lead, one of them ter-
65 minating in a contact 64, normally engaged

by the cab relay armature 48, and the other
leading to battery 65. A conductor 66, from
the opposite side of the battery is connected
with the armature 48, and to simplify the
wiring somewhat, a portion of the main cab
70 circuit may be utilized as a part of the re-
turn conductor of this air valve circuit, and
for this reason one of the conductors 63,
may be joined to the main cab circuit at
point 67.

75 It will be apparent that when for any
reason the cab circuit is broken, the air valve
circuit will be broken at the point 64, by
reason of the falling of the cab relay arma-
ture 48, causing the solenoid 62 to be de-
80 energized, opening the valve 61, and causing
the whistle to be sounded. The whistle is
supplied with steam or air, preferably air,
by means of a branch pipe 68, from a main
pipe 69, the main pipe being in suitable com-
85 munication with the reservoir 70. After the
engineer has received the caution signals in
this manner, he may, if the train has passed
over the insulated joint (which it will prob-
ably have done) by pressing a button or
90 actuating a like circuit closing device 71,
again restore the cab circuit to its originally
closed condition. This restoring device is
connected by conductors 72, in shunt around
the circuit-breaking armature 4, of the cab
95 relay so that if, as has been supposed, the
train has passed the joint and is now on an
electrically continuous piece of track, by
pressing this button the cab circuit will be
completed, the cab relay will be energized,
100 attracting its different armatures and clos-
ing all the cab circuits. The engineer
should then proceed with caution and if the
danger or obstruction has not been removed,
when the next insulated joint is reached the
105 cab circuit will again be broken as the shunt
circuit will be open at the point 30, due to
the deenergization of the second line circuit
relay 40, which relay has been deenergized
110 due to the breaking of its circuit at point
43, as before described. Therefore, assum-
ing the train to have reached this second
joint and the shunt circuit to be open as de-
scribed, the shunt portion of the cab cir-
115 cuit to be open as described, the shunt por-
tion of the cab circuit will again be broken
and visual and audible signals will again
be given to the engineer. These second sig-
nals will also be recorded by the clock so
120 that a perfect check will be kept on the en-
gineer's actions.

A predetermined period of time after the
signals have been given, a time switch de-
vice 73, in the cab, becomes operative to
cause actuation of the means for stopping
125 the train. This device may partake of the
nature of a dash pot and is adjusted to act
sequentially after the giving of the signals.
Throttle controlling circuit wires 74, are
connected to the time switch, one of said
130

wires having a fixed connection therewith at 75, and the other of the wires having a severable connection therewith at 76. A throttle controlling magnet valve 77 is included 5 in this last circuit which is preferably similar to the valve 61. The magnet valve 77 is normally energized by the battery 65, and to simplify the connections, one of the conductors 74, may be connected at 67, to the 10 common return of the main cab circuit and the other of the conductors 74, may be connected at 77', to the common return wire 66, of the air valve circuit 63. It will be seen that the magnet valves 61 and 77 are 15 in reality connected in parallel and both supplied with current from the battery 65, which for this purpose is preferably arranged in multiple-series as shown in the drawings, so as to supply the proper energizing current to both magnet valves. By 20 means of the branch pipe 78, leading from the air valve 61, air is supplied to the time switch 73, and under normal conditions the upper or switch portion of the time switch 25 is upheld by the air pressure and the throttle valve circuit is closed at the point 76. When the air valve circuit is broken however, and the magnet 62 is deenergized to 30 open the valve and cause the whistle to be sounded, the said valve automatically relieves the pressure in the branch pipe 78, and the time switch commences to fall. A predetermined time after the sounding of 35 the whistle the time switch by reason of this sequential action causes a break in the throttle controlling circuit at the point 76. This causes the magnet valve 77 to be deenergized and the fluid under pressure in the pipe 69, flows through the said magnet 40 valve and actuates the throttle controlling device 79 which acting upon the throttle lever 83 shuts off the motive power. And the brakes may then be applied by the admission of fluid under pressure to the brake 45 controlling valve 87. From this it will be understood that signals announcing the existence of any danger are first given to the engineer, a predetermined length of time after the rendering of such signals the motive power is shut off and then the brakes 50 are applied to bring the train to a standstill. The signals are preferably both audible and visual so that the engineer cannot fail to receive them and a check on the actions of the engineer is kept by means of the recording clock, this clock serving in the manner before described, to record the giving of the signal and also by means of an additional wire 88, terminating in a contact 89, to be engaged by the time switch 55 when the same has been actuated, to record the time at which the throttle is closed and the brakes are set. This circuit for recording the actuation of the means for controlling 60 the train is completed from the magnet 65

56, by means of the wire 88, circuit wire 74—66, battery 65, and the wire 59, common to both magnets.

With the use of my system, if a train is in a block a signal will be sent back to the next 70 two sections in rear, giving warning of the occupancy of the said block to any approaching trains and if such warnings are not heeded by the approaching trains, the train controlling devices will operate to 75 stop the approaching trains in time to avert an accident. If for any reason any of the circuits should be broken either accidentally or otherwise, warning of this defect would be communicated to the approaching trains 80 in the same way. Such warnings are all conveyed to the trains by reason of the rupture in the shunt circuit and as this shunt circuit is subject to all track and circuit conditions it will be evident that a defect of any character in either the track or the different circuits, will cause notice to be given of such defects. As the track circuits are all normally closed circuits as soon as the block 85 is cleared or the defect is remedied, the circuits will automatically resume their proper closed condition.

It is important that the main block relay should be fully deenergized when its battery is short circuited by the train in the 95 block so that it will cause, by reason of the dropping of its armature, a positive break in the shunt circuit. In order to insure the complete deenergization of the main block relay, I prefer the use of the connections 100 illustrated in Fig. 3, where I employ at each station a short circuiting conductor 111, connected to the track of the main block and terminating in a contact 112, in the path of the armature 22, of the local block 105 relay. In this case the battery 113, for energizing the main block relay is connected directly across the rails and the armature 22, of the local block relay is connected to the inner rail by the conductor 26, as before. 110 The current from the battery 113, normally energizes the main block relay and if it were not for the additional conductor 111, when the battery is short circuited by the wheels of the train in the block, enough current 115 might still find its way to the main block relay so that the said relay would not be completely deenergized and would therefore fail to break the shunt circuit. The conductors 111—26 in combination with the armature 22, form a low resistance shunt in parallel with the trucks of the train to insure deenergization of the main block relay. This combined conductor 111—26 just described, serves also as a parallel path across 120 the rails for the shunt portion of the cab circuit so that a low resistance connection is also provided across the rails other than by way of the car wheels.

In practice the main cab battery 2, would 130

preferably be greater in strength than the battery 14, in the shunt connection so that if the train should be reversed and the main battery on the train and the battery in the shunt be placed in opposition, although there would be some neutralizing effect, there would be still enough potential to energize the cab relay.

The system is also designed to give warning of the break down of the insulation between any of the blocks. Suppose for instance that the joint 114, should break down. The current from the battery 14, instead of performing its usual function of energizing the relay 35, would flow across the joint 114, to the rail, thence through the shunt and back to the opposite pole of the battery. This deenergization of relay 35, would cause a second deenergization of relay 32, and signals would be sent back as before. Again supposing the joint 115 to become defective in its insulation, the current from the main block battery 25, will flow by combined conductor 26-38 to relay 35, through conductor 37, to the shunt conductor, by the shunt conductor, to the short block, thence to block local battery 19, across the defective joint 115, to opposite pole of battery 25. The battery 19 would be thus connected in opposition and the main block relay thereby failing to receive its proper supply of current would become deenergized and break the shunt connection at the next preceding section. This also would result in the giving of due signals to approaching trains.

The recording device records the time at which the actual train controlling means were actuated, provided of course that such devices were actuated. The record also shows just how long the signals were displayed and how long the actual train controlling means were in force.

For the purpose of rendering the relation of the different circuits more definite I have, in certain of the claims referred to the insulated sections in the relation of their order. Thus I have defined the shunt connection in certain claims as extending from the local block of one section to the main block of the preceding section, and I have described the main block relay of one section as controlling the shunt connection between that section and the next preceding section and being in turn controlled by the local block relay of the succeeding section—that is, the section next ahead in the direction of travel. In the same manner and for this same purpose of making the claims more definite and clear, the line circuits have, for instance, in certain claims been described as extending from a certain section to the second section next preceding that particular section and terminating there in a relay controlling the shunt connection at the forward end of that second

preceding section. It will be apparent that the line circuits are controlled either directly or indirectly by the main and local block relays of the sections through which such line circuits pass. Taking for instance 70 the line circuit 33, we find that it is controlled by the local block relays 20 of the two sections through which it passes and is also controlled by the so-called line controlling relays 35 of these same sections. The 75 line controlling circuits and relays being in turn controlled by the main block relays 23, it can be truthfully said that this circuit is under control of both the main and local block relays. Considering the other line 80 circuit 39, it will be noted that this circuit is directly under the control of the one main block relay 23 at one section and under the control of the main block relay in the next preceding section through the intermediacy 85 of the line controlling relay 35 at the said next preceding section. The main block relays are controlled by the local block relays of the succeeding sections. The circuits thus interlock in a certain sense, so that 90 broadly speaking, the line circuits are actually under the control of both the main and the local block circuits.

What is claimed, is:

1. A track divided by insulation into sections composed each of main and local blocks, a local block circuit having a relay, a shunt connection between the local block of one section and the main block of the preceding section, a main block circuit having a 95 relay controlling the shunt and said main block circuit being under the control of the local block relay of the succeeding section, a line circuit under the control of the main block relay and terminating in a relay controlling the shunt, and a cab circuit arranged to be completed through the traffic tracks and through the shunt connection when the train is passing from one insulated block to another. 100

2. A track divided into insulated sections and each section composed of a main and a local block, a local block circuit having a relay, a shunt connection between the local block of one section and the main block of 105 the preceding section, a main block relay controlling the shunt and under the control of the local block relay of the succeeding section, a line circuit under the control of the main block relay, terminating in a relay controlling the shunt, a cab circuit completed through the track of the main block and through the shunt when passing from a main into a local block. 115

3. A track divided into insulated sections 125 and each section composed of a main and a local block, a local block circuit having a relay, a shunt connection between the local block of one section and the main block of the preceding section, a main block relay 130

controlling the shunt and under the control of the local block relay of the succeeding section, and a line circuit under the control of the main block relay, terminating in a relay controlling a shunt connection.

5. In a train controlling system, a traffic track divided into sections composed each of a main and a local block, a shunt connection between the local block of one section and the main block of the preceding section, a local block circuit including a relay, a main block circuit including a relay to control the shunt connection, line circuits extending each from one section to the second next preceding section terminating in a relay controlling the shunt connection at the forward end of said second section, a line controlling circuit in each section, said circuit including a relay, the line circuits being under the control of the local block relays and the line controlling relays.

6. In a train controlling system, a traffic track divided into sections composed each of a main and a local block, a shunt connection between the local block of one section and the main block of the adjoining section, a local block circuit including a relay, to control the next preceding shunt connection, line circuits extending each from one section to the second next section terminating in a relay controlling the shunt connection at the forward end of said second section, a line-controlling circuit in each section, said circuit including a relay, the line circuits being under the control of the local block relays and the line-controlling relays.

7. In a train controlling system, a traffic track divided into sections composed each of a main and a local block, a shunt connection between the local block of one section and the main block of the preceding section, a local block circuit including a relay, a main block circuit under the control of the local block relay of the succeeding section and including a relay to control the shunt connection aforesaid, line circuits extending each from one section to the second next section terminating in a relay controlling the shunt connection at the forward end of said second section, a line-controlling circuit in each section, including a relay, the line circuits being under the control of the local block relays and the line-controlling relays.

8. In a train controlling system, a traffic track divided into sections composed each of insulated blocks, shunt connections between adjoining blocks of adjacent sections, two block circuits at each section, one of the said block circuits controlling the shunt connection between a given section and the next preceding section and being in turn under the control of the unlike block circuit at the next succeeding section, a line controlling circuit at each section controlled by one of the block circuits aforesaid, line circuits each extending from one section to the second preceding section, terminating at said second preceding section in a relay controlling the shunt connection at the forward end of that section, one line circuit being under the control of like block circuits, and the line controlling circuits of two sections, and the next line circuit being under control of the block circuit of one section and the line controlling circuit of the next preceding section, a cab circuit arranged to be normally completed through the traffic tracks and through the shunt connection when the train is passing from one insulated block to another, and safety devices under control of said cab circuit.

9. In a train controlling system, a traffic track divided into sections composed each

the block circuits aforesaid, and line circuits each extending from one section to the second preceding section, terminating at said second preceding section in a relay controlling the shunt connection at the forward end of that section, one line circuit being under the control of one set of the block circuits and the line controlling circuits of two sections and the next line circuit being under control of a block circuit of one section and the line controlling circuit of the next preceding section.

8. In a train controlling system, a traffic track divided into sections composed each of two insulated blocks, shunt connections between adjoining blocks of adjacent sections, a block circuit at each section controlling the shunt connection between said section and the preceding section, a second block circuit at each section controlling the first block circuit at the preceding section, a line controlling circuit controlled by the first block circuit at each section, line circuits each extending from one section to the second preceding section and terminating there in a relay controlling the shunt connection at the forward end of that second preceding section, the line circuits being arranged in alternating order, with one line circuit under control of the second block circuits and the line controlling circuits of two sections and the next line circuit being under control of the first block circuit of one section and the line controlling circuit of the next section.

9. In a train controlling system, a traffic track divided into sections composed each of insulated blocks, shunt connections between adjoining blocks of adjacent sections, two block circuits at each section, one of the said block circuits controlling the shunt connection between a given section and the next preceding section and being in turn under the control of the unlike block circuit at the next succeeding section, a line controlling circuit at each section controlled by one of the block circuits aforesaid, line circuits each extending from one section to the second preceding section, terminating at said second preceding section in a relay controlling the shunt connection at the forward end of that section, one line circuit being under the control of like block circuits, and the line controlling circuits of two sections, and the next line circuit being under control of the block circuit of one section and the line controlling circuit of the next preceding section, a cab circuit arranged to be normally completed through the traffic tracks and through the shunt connection when the train is passing from one insulated block to another, and safety devices under control of said cab circuit.

10. In a train controlling system, a traffic track divided into sections composed each

of two insulated blocks, shunt connections between adjoining blocks of adjacent sections, a block circuit at each section controlling the shunt connection between said section and the preceding section, a second block circuit at each section controlling the first block circuit at the preceding section, a line controlling circuit controlled by the first block circuit at each section, line circuits each extending from one section to the second preceding section and terminating there in a relay controlling the shunt connection at the forward end of that second preceding section, the line circuits being arranged in alternating order, with one line circuit under control of the second block circuits and the line controlling circuits of two sections and the next line circuit being under control of the first block circuit of one section and the line controlling circuit of the next section, a cab circuit arranged to be normally completed through the traffic tracks and through the shunt connection when the train is passing from one insulated block to another, and safety devices under control of said cab circuit.

11. A train controlling system comprising a traffic track divided into insulated sections and each section composed of a main and local block, shunt connections between the local block of one of said sections and the main block of the adjoining section, main block relays acting to control said shunt connections, local block relays, the local block relay of one section serving to control the action of the main block relay of the adjoining section, and a cab circuit adapted to be normally completed through the traffic tracks, and through the shunt connections when passing from one insulated section to another.

12. A train controlling system comprising a traffic track divided into insulated sections and each section composed of a main and local block, shunt connections between the local block of one of said sections and the main block of the adjoining section, main block relays acting to control said shunt connections, local block relays, the local block relay of one section serving to control the action of the main block relay of the next adjoining section, line circuits extending between the sections, relays in said line circuits acting to control the shunt connections, said line circuits extending successively from one section through one or more sections and being controlled at the sections through which they pass, and a cab circuit adapted to be normally completed through the traffic tracks, and through the shunt connections when passing from one insulated section to another.

13. A traffic track divided by insulation into sections and each section consisting of a main and a local block, a local block cir-

cuit in each section including a relay, a main block circuit in each section including a relay, a shunt connection extending from the local block of one section to the main block of the preceding section, said shunt connection being under the control of the main block relay of the first mentioned section, a line controlling circuit under the control of each main block relay, said line controlling circuits each including a relay, a line circuit extending from the first-mentioned section to the second preceding section and terminating there in a relay controlling the shunt connection at the forward end of that section, said line circuit being under the control of the main block relay of the first-mentioned section and the line controlling relay of the preceding section, a second line circuit extending from the succeeding section through the first-mentioned section to the preceding section and there terminating in a relay controlling the shunt connection at the forward end of said preceding section, said second line circuit being under the control of the local block relays of the said succeeding and said first mentioned sections and under the control of the line controlling relays of said succeeding and said first mentioned sections.

14. A traffic track divided by insulation into sections and each section consisting of a main and a local block, a local block circuit in each section including a relay, a main block circuit in each section including a relay, said main block relay being under the control of the local block relay of the succeeding section, a shunt connection extending from the local block of one section to the main block of the preceding section, said shunt connection being under the control of the main block relay of the first-mentioned section, a line controlling circuit under the control of each main block relay, said line controlling circuits each including a relay, a line circuit extending from the first-mentioned section to the second preceding section and terminating there in a relay controlling the shunt connection at the forward end of that section, said line circuit being under the control of the main block relay of the first-mentioned section, a line controlling circuit under the control of each main block relay, said line controlling circuits each including a relay, a line circuit extending from the first-mentioned section to the second preceding section and terminating there in a relay controlling the shunt connection at the forward end of that section, said line circuit being under the control of the main block relay of the first-mentioned section and the line controlling relay of the preceding section, a second line circuit extending from the succeeding section through the first-mentioned section to the preceding section and there terminating in a relay controlling the shunt connection at the forward end of said preceding section, said second line circuit being under the control of the local block relays of the said succeeding and said first-mentioned sections and under the control of the line controlling relays of said succeeding and said first-mentioned sections.

15. A traffic track divided by insulation into sections and each section consisting of

5 a main and a local block, a local block circuit in each section including a relay, a main block circuit in each section including a relay, a shunt connection extending from the local block of one section to the main block of the preceding section, said shunt connection being under the control of the main block relay of the first-mentioned section, a line controlling circuit under the control of each main block relay, said line controlling circuits each including a relay, a line circuit extending from the first-mentioned section to the second preceding section and terminating there in a relay controlling the shunt connection at the forward end of that section, said line circuit being under the control of the main block relay of the first-mentioned section and the line controlling relay of the preceding section, a second line circuit extending from the succeeding section through the first-mentioned section to the preceding section and there terminating in a relay controlling the shunt connection at the forward end of said preceding section, said second line circuit being under the control of the local block relays of the said succeeding and said first-mentioned sections and under the control of the line controlling relays of said succeeding and said first-mentioned sections, and a cab circuit adapted to be normally completed through the traffic tracks and through the shunt connections when passing from one insulated section to another.

10 16. A traffic track divided by insulation into sections and each section consisting of a main and a local block, a local block circuit in each section including a relay, a main block circuit in each section including a relay, said main block relay being under the control of the local block relay of the succeeding section, a shunt connection extending from the local block of one section to the main block of the preceding section, said shunt connection being under the control of the main block relay of the first-mentioned section, a line controlling circuit under the control of each main block relay, said line controlling circuits each including a relay, a line circuit extending from the first-mentioned section to the second preceding section and terminating there in a relay controlling the shunt connection at the forward end of that section, said line circuit being under the control of the main block relay of the first-mentioned section and the line controlling relay of the preceding section, a second line circuit extending from the succeeding section through the first-mentioned section to the preceding section and there terminating in a relay controlling the shunt connection at the forward end of said preceding section, said second line circuit being under the control of the local block relays of the said succeeding and said first-

mentioned sections and under the control of the line controlling relays of said succeeding and said first-mentioned sections, and a cab circuit adapted to be normally completed through the traffic tracks and through the shunt connections when passing from one insulated section to another. 70

17. A traffic track divided by insulation into sections and each section consisting of a main and a local block, a local block circuit in each section including a relay, a main block circuit in each section including a relay, a shunt connection extending from the local block of one section to the main block of the preceding section, said shunt connection being under the control of the main block relay of the first-mentioned section, a line circuit extending from the first-mentioned section to the second preceding section and terminating there in a relay controlling the shunt connection at the forward end of that section, said line circuit being under the control of the main block relays of the first-mentioned section and of the section preceding the first mentioned section, a second line circuit extending from the succeeding section through the first-mentioned section to the section preceding the same and terminating there in a relay controlling the shunt connection at the forward end of said preceding section, said second line circuit being under the control of the main and local block relays of the said succeeding and first-mentioned sections. 75 80 85 90 95

18. A traffic track divided by insulation into sections and each section consisting of a main and a local block, a local block circuit in each section including a relay, a main block circuit in each section including a relay, a shunt connection extending from the local block of one section to the main block of the preceding section, said shunt connection being under the control of the main block relay of the first-mentioned section, a line circuit extending from the first-mentioned section to the second preceding section and terminating there in a relay controlling the shunt connection at the forward end of that section, said line circuit being under the control of the main block relays of the first-mentioned section and of the section preceding the first-mentioned section, a second line circuit extending from the succeeding section through the first-mentioned section to the section preceding the same and terminating there in a relay controlling the shunt connection at the forward end of said preceding section, said second line circuit being under the control of the main and local block relays of the said succeeding and first-mentioned sections, and a cab circuit adapted to be normally completed through the traffic tracks and through the shunt connections when passing from one insulated section to another. 130

19. A traffic track divided by insulation into sections, each section consisting of a main and a local block, a local block circuit in each section including a relay, a main block circuit in each section including a relay, said main block relay being under the control of the local block relay of the succeeding section, a shunt connection extending between the local block of one section and the main block of the preceding section, said shunt connection being under the control of the main block relay of the first-mentioned section, and line circuits extending between the different sections controlled by the main and local block relays and terminating in relays controlling the shunt connections between the different sections. 65
20. A traffic track divided by insulation into sections, each section consisting of a main and a local block, a local block circuit in each section including a relay, a main block circuit in each section including a relay, said main block relay being under the control of the local block relay of the succeeding section, a shunt connection extending between the local block of one section and the main block of the preceding section, said shunt connection being under the control of the main block relay of the first-mentioned section, and line circuits extending from one section to the second preceding section and terminating there in a relay controlling the shunt connection at the forward end of said second preceding section, the said line circuits being under the control of the main and local block relays in the sections in which the respective line circuits originate and through which they pass. 75
21. In a train controlling system, a traffic track divided into sections composed each of insulated blocks, shunt connections between the adjoining blocks of adjacent sections, main block relays acting to control said shunt connections, local block relays, the local block relay of one section serving to control the action of the main block relay of the next adjoining section, line circuits extending between the sections, relays in said line circuits acting to control the shunt connections, said line circuits extending successively from one section through one or more sections and being controlled at the sections through which they pass. 80
22. A train controlling system comprising a traffic track divided into sections composed each of insulated blocks, shunt connections between the adjoining blocks of adjacent sections, main block relays acting to control said shunt connections, local block relays, the local block relay of one section serving to control the action of the main block relay of the next adjoining section including a relay, a main block circuit in each section including a relay, a shunt connection between the local block of one section and the main block of the preceding section, said shunt connection being under the control of the main block relay of the first-mentioned section, and line circuits extending from one section to the second preceding section and terminating there in a relay controlling the shunt connection at the forward end of said second preceding section, the said line circuits being under the control of the main and local block relays in the sections in which the respective line circuits originate and through which they pass. 85
23. In a train controlling system, a traffic track divided by insulation into sections and each section consisting of a main and a local block, a local block circuit in each section including a relay, a main block circuit in each section including a relay, a shunt connection between the local block of one section and the main block of the preceding section, said shunt connection being under the control of the main block relay of the first-mentioned section, and line circuits extending from one section to the second preceding section and terminating there in a relay controlling the shunt connection at the forward end of said second preceding section, the said line circuits being under the control of the main and local block relays in the sections in which the respective line circuits originate and through which they pass. 90
24. In a train controlling system, a traffic track divided by insulation into sections and each section consisting of a main and a local block, a local block circuit in each section including a relay, a main block circuit in each section including a relay, a shunt connection between the local block of one section and the main block of the preceding section, said shunt connection being under the control of the main block relay of the first-mentioned section, line circuits extending from one section to the second preceding section and terminating there in a relay controlling the shunt connection at the forward end of said second preceding section, the said line circuits being under the control of the main and local block relays in the sections in which the respective line circuits originate and through which they pass, and a cab circuit arranged to be normally completed through the traffic tracks and through the shunt connections when passing from one insulated section to another. 95
